UNITED STATES PATENT OFFICE.

RICHARD WALTER RIDLEY, OF BEAUMONT, TEXAS.

SWING.

Application filed January 27, 1925. Serial No. 5,097.

To all whom it may concern:

Be it known that I, RICHARD WALTER RIDLEY, a citizen of the United States, residing at Beaumont, in the county of Jefferson 5 and State of Texas, have invented certain new and useful Improvements in a Swing, of which the following is a specification.

This invention relates to improvements in swings and has for its principal object to 10 provide one which is adapted for reciprocatory as well as oscillatory movement when the seats are occupied.

One of the important objects of the present invention is to provide a swing of the above 15 mentioned character, which includes a reciprocatory carriage, means being associated with the supporting frame of the swing for limiting the traveling movement of the carriage in either direction so as to prevent the 20 same from becoming disengaged from the frame.

A further object is to provide a swing of the above mentioned character which is simple in construction, inexpensive, and furthermore adapted for the purpose for which 25 the same is designed.

Other objects and advantages of this invention will become apparent during the course of the following description.

In the accompanying drawing forming 30 part of this specification and in which like numerals designate like parts throughout the same:

Figure 1 is a side elevation of the swing 35 embodying my invention.

Fig. 2 is a top plan view thereof.

Fig. 3 is an end elevation, and

Fig. 4 is a sectional view taken approximately on line 4—4, of Fig. 1.

In the drawings, wherein for the purpose 40 of illustration is shown the preferred embodiment of my invention, the numeral 1 designates generally the supporting frames, the same including the spaced vertical standards 2 and 3, each of which includes the leg members 4 and 5 which converge gradually toward their upper ends and are connected together by the cross bars 6. The frame 1 further includes the longitudinally 45 extending parallel spaced beams 7 and 8, the ends of which are secured to the respective cross bars 6 of the standards 2 and 3. Secured on the upper faces of the beams 7 and 8 are the track members 9 and 10 respectively, the purpose thereof hereinafter 50 being more fully described.

A carriage designated generally by the numeral 11 comprises a substantially rectangular frame with suitable bracing means 12 provided therefor as clearly illustrated 60 in Fig. 2. A pair of axles 13 are journaled transversely on the carriage frame adjacent the respective ends thereof. Grooved wheels 14 are secured on the respective ends of each axle and are adapted for cooperation with 65 the track members on the respective beams 7 and 8 whereby the carriage is adapted for reciprocatory movement on the longitudinally extending beams of the supporting frame 1 as will become apparent during 70 the course of the following description.

For the purpose of preventing the carriage traveling beyond the respective ends of the longitudinally extending beams which are of relatively great length, there is provided 75 at each end of the frames a stationary cross bar 15 which extends transversely across the upper edges of the longitudinally extending means and being further secured in the outer ends of the bracket 16, the latter being secured on the beams in a manner clearly illustrated in Figs. 1 and 2. Cooperating with the stationary cross bar 15 is the movable cross bar 17 which extends transversely 80 across the beams and is disposed in the inner ends of the brackets. A pair of coiled springs 18 are interposed between the cross bars 15 and 17 respectively and normally urge the movable cross bar 17 inwardly, the 85 ends of the carriage 11 will engage the inner faces of the movable cross bars 17 depending upon the direction in which the carriage 90 is traveling and the coil springs 18 cooperate with the movable cross bars to provide what I term as bumpers and the same limit the 95 outward movement of the carriage in either direction.

The swings further include a pair of suspension members 19 which are pivotally supported at their upper ends on the opposite sides of the intermediate portion of the carriage 11 on the transversely extending rod 20, the suspension members 19 being disposed adjacent the inner opposed faces 100 of the longitudinally extending beams 7 and 8. The suspension members 19 have their lower free ends spaced from the ground as clearly illustrated in the drawings. A floor forming frame 21 is supported intermediate its ends between the lower ends 105 of the suspension members 19.

A series of transversely extending slats

22 extend across the floor frame 21 and also across the inclined faces of the foot rest 23 which is arranged intermediate the ends of the frame. A rod 24 extends transversely 5 through the sides of the floor forming frame 21 and through the lower portions of the suspension members 19 provides the means whereby the floor forming frame is supported between the lower portions of the 10 suspension members.

Secured at its lower ends on the rod 24 intermediate the side of the floor forming frame 21, is the upright 25. The same is further adapted to be secured to the foot rest piece 23. A horizontally extending bar 26 is supported on the upper end of the upright 25 and suitable handles 27 extend transversely through the respective ends of the horizontal bar. 15

20 A pair of seat members or chairs 28 are supported on the respective ends of the frame 21 on opposite sides of the suspension members 19. A step 29 is supported on each side of the floor forming frame 21 below the same. The forward ledge 30 of the seat or chairs extend below the floor forming frame and provide a means for supporting the step in a manner as clearly illustrated in Fig. 1.

35 A cross piece 31 extends transversely across the frame 21 adjacent each end thereof, the ends of the cross pieces extending outwardly of the sides of the floor forming frame. The purpose of the cross pieces is to provide a means for cooperating with the chains 32, four of such chains, being provided. The upper ends of the chains are secured to the outer ends of the axles 13 and extending downwardly adjacent the outer faces of the longitudinally extending side beams 7 and 8. The lower ends of the chains are secured to the outer ends of the 40 respective cross pieces 31 by means of the eye bolts 33.

45 By having the suspension members 19 disposed on the inside of the longitudinally extending beams 7 and 8 and the chains on the outside thereof, the lateral displacement of the carriage 11 from the tracks on the 50 beams will be prevented.

When the seat or chairs are occupied, it is obvious that when the handles 27 are grasped by the persons seated in the chairs and the persons push forwardly and then rearwardly, the suspension members 19 will be caused to swing or oscillate on the rod 20 which extends through the upper ends of the suspension members and the carriage

11. The momentum thus caused will enable the carriage to reciprocate forward and backward on the track and as heretofore more fully described, the ends of the carriage will strike the movable cross bars or bumpers 17 whereby the outward movement of the carriage in either direction is limited. 60

It will thus be seen from the foregoing description, that a swing has been provided for use in parks, on porches, playgrounds, and the like which will at all times be positive and efficient in its operation. 65

70 While I have shown the preferred embodiment of my invention, it is to be understood that various changes in the size, shape and arrangement of parts may be resorted to without departing from the spirit of the 75 invention and the scope of the appended claims.

Having thus described my invention, what I claim as new is:—

1. In a swing, a supporting frame comprising spaced standards, a pair of parallel spaced longitudinally extending beams secured at their respective ends on the upper portions of said spaced standards, tracks on the upper faces of said beams, a wheeled carriage adapted for reciprocatory movement on said track, means at the ends of said beams for limiting the outward movement of the carriage in either direction with respect to the supporting frame, said last 80 mentioned means comprising a pair of brackets secured on the upper faces of the beam at the respective ends thereof, a stationary cross bar extending transversely across the beams at each end thereof and 85 secured in the respective pair of brackets, a movable cross bar extending transversely within the inner ends of said pair of brackets, coil springs disposed between said cross bars for normally urging the movable 90 cross bar inwardly, and seat members pivotally suspended from said carriage. 95

100 2. In a swing, a supporting frame, a carriage adapted for reciprocatory movement on said frame, suspension means pivotally supported at its upper end on the intermediate portion of said carriage, a pair of seat members supported on the lower ends of said suspension means, and spring urged bumpers arranged on said supporting frame 105 at the ends thereof cooperating with the respective ends of the carriage for limiting the outward movement thereof in either direction with respect to the frame. 110

In testimony whereof I affix my signature.

RICHARD WALTER RIDLEY.
